CLAIM

The ornamental design for an inflatable rocking footrest, as shown.

DESCRIPTION

FIG. 1 is a perspective view of the inflatable rocking footrest of my invention;

FIG. 2 is a front elevation of the inflatable rocking footrest of my invention;

FIG. 3 is a rear view of the inflatable rocking footrest of my invention;

FIG. 4 is a plan view of the inflatable rocking footrest of my invention;

FIG. 5 is an underside plan view of the inflatable rocking footrest of my invention;

FIG. 6 is a right-hand side view of the inflatable rocking footrest of my invention; and,

FIG. 7 is a left-hand side view of the inflatable rocking footrest of my invention.

FIG. 1

FIG. 2

FIG. 3

FIG. 4

FIG. 5

FIG. 6

FIG. 7
